(57) CLAIM

The ornamental design for a control panel for road paving machines, as shown and described.

DESCRIPTION

The patent or application file contains at least one drawing executed in color. Copies of this patent or patent application publication with color drawing(s) will be provided by the Office upon request and payment of the necessary fee.

FIG. 1 shows a view onto the top side of a control panel for road paving machines;

FIG. 2 shows a view onto the bottom side of the control panel of FIG. 1;

FIG. 3 shows a view onto the left side of the control panel of FIG. 1;

FIG. 4 shows a view onto the front side of the control panel of FIG. 1;

FIG. 5 shows a view onto the right side of the control panel of FIG. 1;

FIG. 6 shows a view onto the rear side of the control panel of FIG. 1; and,

FIG. 7 shows a further perspective view onto the front side, left side and bottom side of the control panel of FIG. 1.

1 Claim, 7 Drawing Sheets
